UNITED STATES PATENT OFFICE.

JOHN E. RABER, OF CANTON, OHIO.

WINDOW-GUARD.

1,213,537.

Specification of Letters Patent. Patented Jan. 23, 1917.

Application filed April 29, 1916. Serial No. 94,343.

To all whom it may concern:

Be it known that I, JOHN E. RABER, a citizen of the United States, residing at Canton, in the county of Stark and State 5 of Ohio, have invented a new and useful Window-Guard, of which the following is a specification.

My invention relates to improvements in window-guards and has more especial reference to a guard or a protector for basement or cellar windows or the like through which coal, wood and similar articles are passed, although the device may be employed in various other locations.

15 The object of my invention is the provision of a guard or protector which will protect the glass of a swinging sash when in the open position, and which will automatically fold beneath the glass when the sash 20 is moved into the closed position, allowing the light to pass through the window.

25 A further object is the provision of a guard or protector which is interchangeable with the glass and may be quickly and readily placed in position in the sash in the event that the glass becomes broken.

With these objects in view the invention consists in the novel construction and arrangement of parts, hereinafter described, 30 illustrated in the accompanying drawings, and particularly pointed out in the appended claims, it being understood that various changes in the form, proportions, size and minor details of construction may be made 35 within the scope of the appended claims, without departing from the spirit or sacrificing any of the advantages of the invention.

40 In the accompanying drawings: Figure 1 is a perspective view of a swinging sash provided with my improved guard showing the sash in the opened position, the guard or protector being located in place of the glass. Fig. 2 is a similar view showing the guard or protector opened in front of the glass. 45 Fig. 3 is a vertical section through the swinging sash, showing the sash in the opened position, the guard or protector being shown opened in front of the glass. Fig. 50 4 is a similar view showing the glass in the closed position, the guard or protector being shown folded to allow light to pass through the glass.

Similar numerals of reference indicate

corresponding parts throughout the several 55 figures of the drawings.

Referring more especially to the construction illustrated in the accompanying drawings, the numeral 1 indicates the casing of a window to which is hingedly connected by 60 suitable hinges 2, a swinging sash 3. The hinges 2 are so constructed that the sash will be automatically held in the position shown in Figs. 1 and 2 when said sash is opened but the specific construction of said 65 hinges has no connection with the present invention, it merely being desirable to provide some form of hinge which will hold the sash in the opened position as described.

The sash 3 is preferably formed of cast 70 iron or similar material and is provided with a rectangular opening 4 spaced from which, upon the inner side of the sash, is located a flange 5 extending around the edges of said rectangular opening. A glass 75 panel 6 fits the inner walls of the flange 5, covering the aperture 4 in the sash, said glass panel being held in position as will be hereinafter described.

Guide members 7 are provided adjacent 80 the vertical portions of the flange 5, each of said guide members being provided with an elongated tapered groove 8 open at one extremity as indicated at 9, a relatively short groove 10 being provided in the other 85 extremity of each guide member, said grooves being separated from each other by means of a partition 11. Outwardly disposed off-set ears 12 are provided upon the guide members 7, screws or their equivalents 13 being passed through said ears and secured to the sash 3. Inwardly disposed ears 14 are provided upon the guide members 7, screws 15 being mounted within said ears and provided upon their extremities 90 with caps 16 formed of rubber, fiber or similar material, said caps bearing tightly against the glass panel 6, thus holding said panel in place within the sash.

The guard or protector comprises the 100 hinged members 17 and 18 hingedly connected together by means of hinges 19, the member 17 being provided with an off-set flange 20 adapted to over-lap the adjacent edge portion of the member 18, as best 105 shown in Fig. 3, when the guard is in the opened position. Outwardly disposed pins 21 are provided at the free edge of the pro-

tector member 17 and are slidably mounted within the grooves 10 and similar pins 22 are provided at the free extremity of the member 18, said last named pins being slidably mounted within the grooves 8.

When the sash is in the opened position as best shown in Figs. 2 and 3 the guard or protector members 17 and 18 are opened out in front of the glass panel 6, the weight 10 of the guard being supported by the pins 21 resting upon the partitions 11. As the sash is moved into the closed position the members 17 and 18 will automatically fold toward each other, the pins 22 upon the 15 member 18 moving through the grooves 8 in the guide members and coming to a stop in engagement with the partitions 11, the pins 21 upon the guard member 17 moving the length of the grooves 10 and coming to a 20 stop at the lower closed extremities of said grooves as shown in Fig. 4, said guard or protector being in the folded position, permitting light to pass through the glass panel 6 unobstructed. As the sash is moved into 25 the raised position the protector will automatically open by reason of its weight, the pins 21 upon the member 17 moving the length of the grooves 10 and resting upon the partitions 11, the pins 22 upon the member 18 moving through the grooves 8 as the 30 members 17 and 18 assume a vertical position as shown in Fig. 3. When in this position the guard will protect the glass panel 6, preventing wood, coal or other material which would be likely to damage said panel from coming into contact therewith.

In the event that the glass panel 6 should accidentally become broken the glass may be removed from the sash and the guard removed 40 from the guide members 7 and placed within the sash as shown in Fig. 1. In order to accomplish this the screws 13 in one of the guide members should be loosened, allowing said guide member to be loosened from the sash 45 and the guard would be removed from the guide members. The screws 15 in the other guide member are then loosened sufficiently to allow the removal of the broken glass from the sash after which the guard is reversed 50 and placed within the sash in place of the glass, the loosened guide member being again connected to the sash and the screws 15 tightened upon the guard, holding the same firmly in position.

55 A suitable latch 23 may be provided upon the free edge of the sash 3 for the purpose of locking the sash in the closed position but the specific construction of this latch has no bearing upon the present invention.

60 Although the drawings and above specification disclose the best mode in which I have contemplated embodying my invention I desire to be not limited to the details of such disclosure, for, in the further practical application of my invention, many 65

changes in form and construction may be made, as circumstances require or experience suggests, without departing from the spirit of the invention, within the scope of the appended claims.

70 I claim:

1. In a device of the character described, the combination with a hinged member adapted to swing in a vertical plane, of a guard member hingedly connected at its upper edge to said hinged member and a second guard member hingedly connected to the lower edge of said first named guard member, the lower edge of said second named guard member being slidably connected to said hinged member, said guard members adapted to fold against the hinged member when the latter is raised and to unfold therefrom when the latter is lowered.

75 2. The combination with a swinging closure member for an opening, said member having delicate parts, of a guard member hingedly connected to said closure member below said delicate parts when the closure member is in the closed position, and a second guard member hingedly connected to said first named guard member, the free edge of said second named guard member being slidably connected to said closure member, said guard members adapted to 80 fold against the closure member when opened to protect its delicate parts, and to unfold therefrom in unobstructing position relative to the opening when the closure member is closed.

85 3. The combination with an opening and a closure member hinged at one side thereof for vertical swinging movement, of a protecting element comprising a plurality of hingedly connected members hinged to the 90 inner side of the closure member the free edge of the lowermost member being slidably connected to the closure member, said hingedly connected members adapted to open against said closure member when the 95 closure member is opened and to fold together through the opening when the closure member is closed.

105 4. In a device of the character described, a window casing, a vertically swinging sash frame hinged to said window casing, a glazed panel mounted within said sash frame, and a guard formed of sections hingedly connected together and hingedly connected to said sash frame, the edges of 110 said guard being slidably connected to said sash frame, said guard arranged to open in front of said glazed panel when the sash is in the raised position and to fold together beneath said glazed panel when the sash is 115 in the closed position, one of said sections provided with an off-set portion adapted to overlap the hinged joint of said sections when the guard is in the opened position.

120 5. In a device of the character described,

a window casing, a sash frame hinged at one side thereof for vertical swinging movement, said sash frame being provided with vertically disposed grooves, a guard formed of 5 sections hingedly connected together and hingedly connected to said sash frame adjacent the lower extremities of said grooves, and projections provided adjacent the free edge of said guard and slidably located 10 within said grooves, said sections being arranged to automatically fold together beneath said glazed panel when the sash is in the closed position and to automatically open in front of said glazed panel when the 15 sash is in the raised position.

6. In a device of the character described, a window casing, a sash frame hinged to the casing, a glazed panel mounted within said sash frame, a vertically disposed guide member 20 located adjacent each vertical edge of said glazed panel, each of said guide members being provided with an elongated groove and a relatively short groove, screws provided upon said guide members and 25 adapted to hold said glazed panel in position within the sash, a guard comprising sections hingedly connected together, pins

mounted upon the upper section of said guard and slidably mounted within the relatively short grooves and pins carried by the 30 lower section of said guard and slidably mounted within the relatively long grooves.

7. In a device of the character described, a window casing, a vertically swinging sash frame hinged to the casing, a glazed panel 35 mounted within said sash frame, a vertically disposed guide member detachably secured adjacent each vertical edge of said glazed panel, each of said guide members being provided with a groove, means upon said guide 40 members for retaining said glazed panel within the sash, a guard formed of sections hingedly connected together and hingedly connected to said guide members adjacent the lower edge of said grooves, and pins carried at the free edge of the lower section of 45 said guard and slidably mounted within the grooves in said guide members said guard being adapted to be substituted in place of said glazed panel. 50

In testimony that I claim the above, I have hereunto subscribed my name.

JOHN E. RABER.
